FIG. 1 is a top plan view of the combined carrying case accessory tray and lid for a sewing machine or similar article showing my new design completely assembled;

FIG. 2 is an end elevational view thereof, both ends being identical;

FIG. 3 is a front elevational view thereof, both front and rear being identical; and

FIG. 4 is a perspective view thereof;

FIG. 5 is a top plan view with the accessory tray and lid removed;

FIG. 6 is an end elevational view thereof, both ends being identical;

FIG. 7 is a front elevational view thereof, both front and rear being identical;

FIG. 8 is a bottom view thereof; and

FIG. 9 is a perspective view thereof;

FIG. 10 is a top plan view of the accessory tray;

FIG. 11 is a left end elevational view thereof;

FIG. 12 is a front elevational view thereof, the front and rear being mirror images one of the other;

FIG. 13 is a right end elevational view thereof;

FIG. 14 is a bottom plan view thereof; and

FIG. 15 is a perspective view thereof;

FIG. 16 is a top plan view of the lid;

FIG. 17 is a front elevational view thereof, the front and rear being identical;

FIG. 18 is an end elevational view thereof, both ends being identical;

FIG. 19 is a bottom view thereof; and
FIG. 20 is a perspective view thereof;

FIG. 21 is a top plan view of the carrying case with the accessory tray in place but with the lid removed;

FIG. 22 is an end elevational view thereof, both ends being identical;

FIG. 23 is a front elevational view thereof, the front and rear being mirror images one of the other; and

FIG. 24 is a perspective view thereof.

I claim:

The ornamental design for a combined carrying case accessory tray and lid for a sewing machine or similar article, substantially as shown and described.
